CLOTHES BUREAU

Raymond Loewy, 39 Avenue d'Iéna, Paris 16ème, France

Filed Oct. 18, 1968, Ser. No. 14,049

Term of patent 7 years

Int. Cl. D6—01

U.S. Cl. D33—6

FIG. 1

FIG. 2

FIG. 3

FIG. 4

FIG. 5

FIGURE 1 is a perspective view showing the clothes bureau of the present invention;

FIGURE 2 is another perspective view of the clothes bureau, showing the bureau in an open position;

FIGURE 3 is a front elevational view of the closed bureau;

FIGURE 4 is a side elevational view of the closed bureau; and

FIGURE 5 is a top plan view of the closed bureau.

The back of the bureau is plain, and the bottom of the bureau is plain apart from the illustrated supports.

I claim:

The ornamental design for a clothes bureau, as shown and described.
